UNITED STATES PATENT OFFICE.

JOHN RAE, OF OCEAN FALLS, BRITISH COLUMBIA, CANADA.

WOOD-CHIPPING MACHINE.

Application filed May 15, 1926. Serial No. 109,404.

My present invention relates to improvements in a wood chipping machine of the type commonly used for the purpose of cutting wood into chips preparatory to making pulp therefrom and appertains more particularly to a chute feeder therefor whereby the blocks of wood to be chipped are fed by gravity to a rotary knife-carrying disk.

It is common practice in wood chipping machines of this general type to provide a horizontal stationary knife associated with the spout to coact with the rotary cutting elements, the same being adjustable to compensate for wear incidental to the action of the blocks of wood during the operation of the machine. In use, such a machine is constantly requiring adjusting and replacements due to the excessive wear on the stationary knife at one point for when such knife is arranged horizontally the block is thrown violently against it every time a blade on the rotary cutter strikes the block and this impact against the stationary knife is focused pretty much on one point. Consequently a certain part of the stationary knife is soon worn down by this unnecessarily severe treatment and the blade rendered useless.

A further disadvantage of this type of chipper is that totally inadequate and often times no provision at all is made to care for wear on the inner end of the feed spout as it approaches the knife and where such wear is occasioned; it frequently happens that the whole spout is discarded when the thrashing of the blocks on a limited area of the mouth of the spout has so worn it that it has to be consigned to the scrap heap.

The objects of this invention are to provide an improved spout wherein the associated fixed knife is angularly disposed and readily adjustable; adequate provision is made for replacing worn sections of the spout and in which the spout as a unit is of generally improved construction comprising few and relatively simple parts, any of which are movable being readily accessible.

To the accomplishment of these and related objects, the invention resides in the construction, combination and arrangement of the several co-operating elements as shall be hereinafter more fully described, illustrated in the accompanying drawings and pointed out in the claims hereunto appended.

The invention can be best described and will be most readily understood when refer-

ence is had to the attached drawings in which,

Fig. 1 is a side elevation of a wood chipper embodying my improved chute;

Fig. 2 is an end elevation thereof; and

Figs. 3, 4 and 5 are a front elevation, plan and side elevation respectively of the chute.

In this apparatus a suitable bed is provided to support a rotatable disk in which a number of knives are arranged and an inclined chute disposed eccentric to the cutting disk that it so feeds to the same, the delivery mouth of such chute just clearing the knives of said rotary disk. This chute, eccentric to the axis of the rotary cutter, is inclined sufficiently to feed the wood blocks by gravity to the rotating knives and arranged at an angle to the vertical plane. The rotary knives therefore do not cut directly across the grain, nor yet with it but at an angle thereby eliminating to a large degree the breaking of the wood into splinters, splits, wood dust and the like, the presence of which constituents in the wood chips when the same go into the pulp lowers the quality of the pulp so that the limiting, to as nearly total exclusion as possible, of the production of these elements is to be desired.

The usual harmful effects accompanying the thrashing of the wood blocks in the spout are also lessened by forming the spout particularly at the feed end as a V-shaped trough in which each block settles to find a conformable support or bed. The portions of these walls adjoining the delivery end are both adjustable and replaceable to allow of advancement to give the desired support to the block and removal when badly worn. In this way not only is the amount of wear on the feed end of the spout, occasioned by pounding or thrashing, materially curtailed but ample provision is made for caring for such as is inevitable while preserving the usefulness of the spout as a whole.

Supporting the fixed knife at an incline so that its exposed or cutting edge is angular to the horizontal plane has very marked advantages in imparting, in co-operating with the rotating knives, a shearing cut rather than a direct chipping blow. The cutting of chips free those undesirable elements that lower the grade of the pulp; lengthening the life of the knife by distributing the wear over a greater surface and incidentally saving time wasted in the un-

necessarily frequent adjusting and replacing of the knife; and the production of greater speed from the rotary cutter by reducing the resistance of each chipping blow are the principal features of the inclined knife but the reduction of vibration and the obtaining of higher efficiency in general are likewise attributes of this improved design.

Referring now particularly to the drawings wherein like characters indicate like parts throughout the several views, the invention is shown as comprising a bed or foundation support 6 on which a rotatable shaft 7 and a feed chute 8 are mounted. The shaft is suitably journalled as at 9 and carries a keyed disk 10, on which radially disposed knives 11 are mounted near its periphery near and associated with each of which is a slot 12, and a belt pulley 13 for connection with a power source not shown. The knives 11 project from the surface of the disk a predetermined distance, such setting depending on the thickness of the chip desired and the slots provide an outlet passage for the chips that fall into a prepared pit. A suitable guard 14 encloses the upper half of the disk cutter 10.

The chute 8 is disposed eccentrically to the shaft 7 and so inclined as to feed the wood blocks to the chipper disk 10, with which its delivery end communicates, by gravity. The same comprises a shoe 15 having a flange 16, by which it is firmly anchored to the bed 6, extending around both sides and the back, but terminating flush with the mouth 17 of the spout confronting the rotary chipper. The chute inclines upwardly as an arm from the delivery mouth and angularly from the vertical plane of the longitudinal median of the shoe. This part of the chute is formed as a trough 18 substantially V-shaped and is cut away at the mouth 17 to receive the square plates 19, removably fastened with countersunk screws 20, that lie smooth with the face of the trough and terminate flush with the mouth. The slots 21 in said plates adapted to receive the retaining screws may be elongated to render the same adjustable. A removable top 22 is provided, for the trough 18, extending from the mouth to the tail of the chute and carries a handle part 23. Locking members 24 serve to retain the same in place; the top of the chute being thus removable, easy access is provided to the replaceable plates 19.

The shoe 15 near its base has a cut from front to back and extending the width of the trough to accommodate a fixed knife 25 that is inclined, one side being raised considerably above the other, for a purpose hereinbefore described, but that longitudinally lies horizontal. This knife 25 which underlies the trough 18 is movable longitudinally to compensate for wear and also to permit a

close adjustment of it with relation to the co-operating knives on the rotary disk 10, it being advantageous, to secure the best shearing, to have no gap at all between the fixed and moving knives. Accordingly, a regulating stem 26, suitably connected to the rear end of the knife 25, is threaded in an upstanding extension 27 of the rear flange 16 and adapted on rotation to advance to retard the knife. A set screw 28 located in the top of said extension 27 designed to engage the stem acts as a clamp therefore. It will be obvious that the size and shape of the wood blocks being fed to the chipper will have an influence on the relation of the position of the cutting edge of the fixed knife to the mouth of the trough for not every block will settle into contact with the apex of the V sides, consequently the cutting edge of the fixed knife should be adjustable to allow of so positioning this edge that the same will lie in the path of a projection from the line on the lower side of the block being chipped if maximum support for the said block is to be provided.

From the foregoing description taken in connection with the accompanying drawings, it will be manifest that a wood chipping machine is provided which will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

What I claim as new is:

1. A chipper comprising a rotary knife-carrying disk; a triangular feed chute with a flat removable inclined top, the mouth of said chute being eccentric to the axis of said disk and projecting to just clear the knives of the latter; and a fixed knife disposed angularly to the horizontal plane and adapted to coat with the knives of said disk.

2. In a chipper as described, the combination of a rotary knife-carrying disk; an inclined feed chute with a flat inclined removable top and a replaceable bottom, said chute being adapted to convey the wood blocks into contact with the knives of said disk, comprising a shoe having a retaining flange about both sides and the back and a trough part that in addition to being inclined from the horizontal plane is angular to the vertical plane from the longitudinal median of the shoe; and an adjustable stationary knife adapted to be advanced into the path of a projection from the line of the under side of a block being fed to the chipper.

3. In a chipper as described, the combination

tion of a rotary knife-carrying disk; an inclined feed chute with a flat inclined removable top and a replaceable bottom, said chute being adapted to convey the wood blocks 5 into contact with the knives of said disk, comprising a shoe having a retaining flange about both sides and the back and a trough part that in addition to being inclined from the horizontal plane is angular to the vertical plane from the longitudinal median of 10 the shoe; a cut through said shoe from front to back and extending the greater part of the width thereof, the same being higher at one side than the other; an adjustable stationary knife adapted to project through 15 said cut; and means for regulating the longitudinal position of the last mentioned knife.

In testimony whereof I hereunto affix my signature.

JOHN RAE.
